(57) **CLAIM**

The ornamental design for a handle for fuel can, as shown and described.

DESCRIPTION

FIG. 1 is a top plan view of the handle for fuel can;

FIG. 2 is a bottom plan view thereof;

FIG. 3 is a side elevational view thereof in an enlarged scale, the opposite side being a mirror image;

FIG. 4 is a front view thereof in an enlarged scale;

FIG. 5 is a back view thereof in an enlarged scale;

FIG. 6 is a top isometric view thereof;

FIG. 7 is a right top isometric view thereof;

FIG. 8 is a bottom isometric view thereof;

FIG. 9 is a right bottom isometric view thereof; and,

FIG. 10 is a top isometric view of the handle for fuel can in a reduced scale. The broken line showing of the environment is for illustrative purposes only and forms no part of the claimed design.
